US00D703061S

(12) United States Design Patent
de Lima Paschoal et al.

(10) Patent No.: US D703,061 S
(45) Date of Patent: * Apr. 22, 2014

(54) CONTAINER

(71) Applicant: Natura Cosmeticos S.A., Itapecerica da Serra - SP (BR)

(72) Inventors: Juliana de Lima Paschoal, Campinas - SP (BR); Maria Filomena Padron Miozzo, Campinas - SP (BR); Frederico de Carvalho L'Abbate, Sao Paulo SP (BR); Anderson Alan Liba, Jundiai SP (BR)

(73) Assignee: Natura Cosmeticos S.A., Itapecerica da Serra SP

() Term: 14 Years

(21) Appl. No.: 29/468,606

(22) Filed: Oct. 1, 2013

Related U.S. Application Data

(62) Division of application No. 29/383,324, filed on Jan. 14, 2011, now Pat. No. Des. 693,226.
